United States Patent Office.

E. P. RUSSELL, OF MANLIUS, NEW YORK.

Letters Patent No. 68,461, dated September 3, 1867.

IMPROVEMENT IN DUMPING-REELS FOR HARVESTERS.

The Schedule referred to in these Letters Patent and making part of the same.

TO ALL WHOM IT MAY CONCERN:

Be it known that I, E. P. RUSSELL, of Manlius, in the county of Onondaga, and in the State of New York, have invented certain new and useful Improvements in Reel-Dumpers or Doppers for Harvesters and Reaping Machines; and I do hereby declare that the following is a full, clear, and exact description thereof, reference being had to the accompanying drawings, forming a part of this specification. In the drawings—

Figure 1 is a perspective view, and

Figure 2 is a side elevation, the operation being shown in red lines.

This invention is an improvement upon the reel-dumper patented to me 1866, and principally consists in raising both ends of the reel-shaft at the same time, and in the position of the rear ends of the dumper-fingers, and the upward and backward movement of the reel in discharging the gavel.

In the drawing A represents the general framework of the harvester; B the cutter-bar; C the standards which bear the dumper; D is the shaft of the revolving cradles or dumper-reel; E E are two arms keyed at right angles to the shaft D, and support the two revolving cradles F. These cradles F are made of suitable slats of sufficient length, and their supports E are of such a length that when the cradle is in the position for receiving the cut grain, the points of the fingers shall be at a point nearly touching the rear of the cutter-bar, and the opposite ends of the fingers shall be inclined upward and backward to a point considerably in rear of the shaft D, as shown in drawings. At the ends of the shaft are affixed double-end cam levers G G, which play upon the plates H H, attached for that purpose to the standards C by a half revolution of the dropper-shaft, causing the shaft to rise clear of any obstacles, and discharge the bundle. I I are two short levers pivoted at the upper and rear ends of the standards. In the other ends of these levers are the bearings of the shaft D. J J are guide-arms on each standard, and they pass between and guide the levers G and I. On one of the levers, G, at its opposite ends, are projecting arms K, to receive the action of the tripping device. L is the tripping crank, turning freely on one end of the shaft D. In the other end of the crank L is a spring-bolt, N, with a bevelled face, so that when thrust backward it may slip past the arm K. The operative foot-lever is attached to the stud *a* on the end of crank L.

In the operation of my invention, as the grain is cut it falls upon the cradle F. When the driver sees that enough for a gavel is cut, he pushes the operative lever with his foot or hand, which makes the bolt N of lever L pull against the arm K of lever G, thereby causing the lower ends of levers G and I to rise, raising with them both ends of the shaft D, thereby giving an upward and backward movement to the cradle, upon which the gavel lies. As the pressure of the foot or hand continues, the cradle F is made to half revolve, and thus drops the gavel, the other cradle taking its place almost instantaneously.

By the arrangement described of the cradle-fingers, and the raising of both ends of the shaft and cradle, I am enabled to get an upward, backward, and drawing motion, which discharges the grain in the best and easiest manner.

Having fully described my invention, what I claim as new, and desire to secure by Letters Patent, is—

1. Raising the cradle-shaft at both ends at the same time that the cradles are revolved and carried backward by means of cam G, plate H, and crank L, substantially as and for the purposes set forth.

2. Cams G, plates H, lever I, arms J, and crank L, combined and operating substantially as described.

In testimony that I claim the above-described invention I have hereunto signed my name this 24th day of September, 1866.

E. P. RUSSELL.
